DESIGN FOR A COMBINATION COMB AND MANICURING IMPLEMENT

Hamell J. Suhadolc, Hoboken, N. J.

Application March 5, 1937, Serial No. 68,023

Term of patent 3½ years

To all whom it may concern:

Be it known that I, Hamell J. Suhadolc, a citizen of the United States and a resident of Hoboken, county of Hudson, State of New Jersey, have invented a new, original, and ornamental Design for a Combination Comb and Manicuring Implement, of which the following is a specification, reference being had to the accompanying drawing, forming part thereof, and in which,

Fig. 1 is a side elevational view of a combination comb and manicuring implement showing my new design,

Fig. 2 is a top view, and

Fig. 3 a cross-sectional end view taken on line 3—3 in Fig. 1.

I claim:

The ornamental design for a combination comb and manicuring implement, as shown.

HAMELL J. SUHADOLC.
